To all whom it may concern:

Be it known that I, Luther I. Replogle, a citizen
of the United States, residing at Oak Park, in
the county of Cook and State of Illinois, have
invented a new, original, and ornamental De-
sign for a Phonograph Record Holder, of which
the following is a specification, reference being
had to the accompanying drawing, forming
part thereof:

The figure is a perspective view of a phono-
graph record holder embodying my new design.

I claim:

The ornamental design for a phonograph rec-
ord holder, as shown.
